UNITED STATES PATENT OFFICE.

ADOLPHUS BERNHARDT HEYDRICH, OF ALLERTON, IOWA, ASSIGNOR OF ONE-THIRD TO DAVID D. SHIRLEY AND ONE-THIRD TO OTTO HEYDRICH, OF ALLERTON, IOWA.

CARPET-FASTENER.

No. 890,513.

Specification of Letters Patent.

Patented June 9, 1908.

Application filed August 27, 1907. Serial No. 390,268.

To all whom it may concern:

Be it known that I, ADOLPHUS B. HEYDRICH, a citizen of the United States, and resident of Allerton, in the county of Wayne and 5 State of Iowa, have invented an Improvement in Carpet-Fastening Devices, of which the following is a specification.

This is an improvement in carpet fastening devices and consists in certain novel constructions and combinations of parts herein- 10 after described and claimed.

Referring to the drawing forming a part hereof, Figure 1 is a perspective view of a portion of a room provided with my improved fasteners. Fig. 2 is a plan view of 15 the fastener in closed position. Fig. 3 is a rear view with the fastening device in inoperative position. Fig. 4 is a perspective view of one of the fasteners. Fig. 5 is a central longitudinal section. 20

My improved fastener comprises a semi-circular plate A, provided on its straight side with a pair of longitudinally aligned bearings a spaced apart from each other, and on its 25 curved side with a slot a' for receiving a tack whereby to secure the plate to the floor. Holes a³ are also provided in the plate for receiving additional tacks if necessary.

A rod B is journaled in the bearings, the 30 ends b of the rod being bent at a right angle thereto, and the said ends are also curved and pointed as shown in Figs. 1 and 4, for a purpose to be hereafter described.

The central portion of the rod is formed 35 into an open loop b², to form a cranked portion whereby to rotate the rod in the bearings, and the resiliency of the rod tends to force the sides of the loop into firm contact with the adjacent ends of the bearings, and 40 the said bearings are provided with notches b³ and b⁴, the notches b³ being engaged by the sides of the loop when the said loop is in a vertical position, and the notches b⁴ being engaged thereby when the loop is in a horizontal 45 position.

In practical use, the floor is provided with the fasteners at spaced intervals, and the carpet is engaged with the pointed ends of the rod. The rod is then turned into a horizontal 50 position, as shown in Fig. 5, thus drawing the carpet toward the wall, and the pointed ends of the rod pass through the carpet from below upward and again from above downward into engagement with the 55 floor, thus clamping the carpet securely to

the floor, the edge of the carpet lapping over the fastener and hiding all of it from view except the bent ends of the rod.

It will be understood that the fasteners are arranged with their straight sides toward the wall, and that when the cranked portion of the rod is turned into the horizontal position, it is locked into such position by the engagement of the sides of the loop with the notches in the ends of the bearing. 60

In Fig. 4, the fastener is shown fastened to the floor, by means of a staple instead of by a tack, and in this construction the plate is cut away at the sides, as shown in Fig. 4, instead of being semi-circular as shown in 70 Fig. 2.

If desired, the locking notches of the bearings might be omitted, and the hooks tightened in place by contracting the bearings after the carpet is secured in position. 75

In using the device, the holders are secured to the floor at suitable intervals in the position shown in Fig. 1 of the drawing. The carpet is then drawn up toward the wall and a portion of the carpet somewhat back from the edge is engaged with the points b, after which the arm b² is drawn toward the wall until it contacts with the floor, this movement moving the points b upwardly through the carpet and downwardly through the same 85 so that only a small portion of the said points appear on the surface of the carpet as shown at the left of Fig. 1.

It will be evident from the description that all of the fastener is concealed beneath the 90 carpet except the above mentioned small portion of the points.

I claim:

1. A device of the class described, comprising a plate adapted to be placed beneath the carpet and provided with means whereby it may be secured to a floor, and with bearings spaced apart longitudinally from each other, a rod journaled in the bearings, said rod having its ends pointed and bent at an angle to the rod, the central portion of the rod being bent into an open loop, and said loop being arranged between the bearings, the adjacent ends of the bearings being notched to receive the sides of the loop when 95 said loop is in a horizontal position for the purpose set forth, said bent portions being curved to pass first upwardly and then downwardly through the carpet when the loop is in a horizontal position. 105

2. A device of the class described, comprising a plate adapted to be placed beneath the carpet and to be attached to a floor, said plate being provided with longitudinally aligned bearings spaced apart from each other, a rod journaled in the bearings, means whereby to rotate the rod, said rod having its ends pointed and curved and bent at an angle to the rod, and adapted to pass upwardly and

downwardly through the carpet when the 10 rod is rotated, and means for locking the rod with the bent portions thereof in substantial parallelism with the floor.

ADOLPHUS BERNHARDT HEYDRICH.
